UNITED STATES PATENT OFFICE

PETER F. SCHNEIDER, OF SAN FRANCISCO, CALIFORNIA, ASSIGNOR TO TRANSIT
MIXERS, INC., OF SAN FRANCISCO, CALIFORNIA, A CORPORATION OF NEVADA

CONCRETE MIXER

Application filed June 22, 1929. Serial No. 372,944.

My invention relates to the general class of mixing machines, and particularly to machines especially adapted for mixing concrete, in terms of which art I shall, for example, 5 herein describe it.

One object of my invention is to feed the constituents of the concrete into the mixer member with a desirable evenness and spread, conducive to an intimate mix.

10 Another object is to discharge the completed mix by a mere reversal of the rotative direction of the infeeding and mixing operation.

Another object is to effect and to regulate 15 the discharge of the mix, both in time and amount, without having to tilt the mixing drum.

Another object is to provide a simple and effective mixing machine.

20 To these ends my invention comprises a mixing member adapted for rotation about its axis in either direction; a stationary feed hopper registering through one opening with said mixing member, and through another 25 opening communicating with the exterior; a conveyor within the hopper connected with and deriving simultaneous rotation from the mixing member, said conveyor being adapted, according to the direction of its rotation, to 30 selectively direct the infeeding constituents into the mixing member, or to direct the mix through the discharge opening to the exterior; and a gate to control the discharge opening and the mix delivered therethrough.

35 In the accompanying drawings I have shown my machine in its preferred form, though it is to be understood that changes may be made therein in structure, arrangement and combination without departing 40 from the spirit of my invention as defined by the claims hereunto appended.

In the drawings

Figure 1 is a vertical, longitudinal section of the machine, the mixing drum being fragmentary as to its length, mounting and interior instrumentalities.

Figure 2 is a vertical section on the line 2—2 of Fig. 1.

50 1 is a drum in which the concrete constituents are mixed. Since, in the main, it does

not differ from the well known mixing drums of the art, I have not deemed it necessary to illustrate it in detail, it being sufficient for the present disclosure to say that it is a shell mounted for rotation in either direction and 55 having within it such mixing members as are commonly used. A portion of a frame 2 of the machine is here shown.

The drum in the present case, at one end is a frustum 3, having an open extremity. 4 is 60 a stationary feed hopper carried by the braces 5 from the frame 2. The throat of the hopper is approximately cylindrical with two openings, one in its bottom communicating with the exterior, and another in its side registering with the open extremity of the frustum 3 of the mixing drum. The throat is formed by a closed front wall 6, Fig. 1, ar- 65 cuate side walls 7, Fig. 2, and the open lower end of the rear wall 8. About the opening 70 in the side of the hopper throat is a flange 9 of angle section. Secured to the open ex- tremity of the drum frustum 3 is a journal fitting 10, of a section adapted to embrace, and with the addition of a bolted ring 11, to 75 confine the flange 9 of the hopper throat, thereby forming a journal coupling between the rotating drum and the fixed hopper. 12 is a screw conveyer, lying and operating with- 80 in the throat of the hopper. The rear end of the screw conveyer is fixed at 13 to the drum frustum and its front end is fixed to a bearing 14 pivotally mounted for rotation in the front wall 6 of the hopper throat. Thus the screw conveyer rotates with the drum. 15 is 85 a gate mounted in grooved slides 16 at the lower edges of the side walls 7 of the hopper throat, said gate controlling the open bottom of the throat. 17 is a lever connected by a link 18 with the gate 15, whereby said gate 90 is operated.

19 is a chute carried by the side walls 7 of the hopper throat. The operation of the ma- 95 chine is as follows:

The several constituents to be mixed are supplied to the hopper 4, and passing down into the throat, the bottom opening being then closed by the gate 15, are, by the screw conveyer 12, rotating in one direction, carried back through the side opening of the 100

throat into the frustum 3, and delivered into the rotating drum 1, with a general spread and evenness in contrast with a direct dump, as would be the case if they were delivered 5 directly from the hopper into the mixing section of the drum.

When the mixing of the charge is complete, the rotation of the drum 1 is reversed, whereby the mix passes outwardly into and through 10 the frustum 3 and through the registering communication of frustum with the throat, into said throat. The screw conveyer 12, rotating the reverse of its infeed operation, directs the mix to and through the bottom opening 15 of the throat, the controlling gate 15 of said opening having been opened to permit the discharge of the mix into the chute 19. By properly regulating the gate 15 with respect to the extent of its opening, the discharge 20 of the mix and its control both in time and quantity is thus possible without having to tilt the mixing drum, as in common practise.

I claim:—

1. A mixing machine comprising a mixing member; a material-feeding member having one opening in communication with the mixing member and another opening communicating with the exterior; a conveying member 25 within the feeding member adapted to selectively direct the material through either opening; and means for controlling the opening to the exterior.

2. A mixing machine comprising a mixing 35 drum; a feed hopper having one opening in communication with the mixing drum and another opening communicating with the exterior; a rotatable screw conveyer within the hopper disposed, in accordance with its direction of rotation, to selectively direct material through either opening; and a gate for controlling the opening to the exterior.

3. A mixing machine comprising a rotatable mixing drum; a feed hopper having one 45 opening in communication with the mixing drum and another opening communicating with the exterior; a screw conveyer connected with and deriving rotation from the mixing drum, said conveyer being disposed within the hopper to selectively direct material through either opening according to its direction of rotation; and a gate for controlling the opening to the exterior.

4. A mixing machine comprising a mixing 55 drum having an open end; a hopper having a throat with a bottom opening and a side opening, the latter registering with the open end of the mixing drum; a conveyer within said throat adapted to selectively direct material through the side opening or the bottom opening; and a gate for controlling the bottom opening.

5. A mixing machine comprising a rotatable mixing drum having an open end; a hopper 65 having a throat with a bottom opening

and a side opening, the latter registering with the open end of the mixing drum; a rotatable screw conveyer within the throat adapted for selectively directing material through the side or the bottom opening of the throat according to its direction of rotation; and a gate for controlling the bottom opening of the throat.

6. A mixing machine comprising a rotatable mixing drum having an open end; a hopper having a throat with a bottom opening and a side opening, the latter registering with the open end of the drum; a rotatable screw conveyer within the throat adapted for selectively directing material through either opening according to its direction of rotation, said conveyer being connected with and deriving its rotation from the mixing drum; and a gate for controlling the bottom opening of the throat.

7. A mixing machine comprising a rotatable mixing drum one end of which is a frustum with open extremity; a stationary feed hopper having a throat with a bottom opening and a side opening, the latter registering with the open extremity of the frustum of the mixing drum; a journal connection between said registering parts; a rotatable screw conveyer within the throat adapted for selectively directing material through either opening; and a gate for controlling the bottom opening of the throat.

8. A mixing machine comprising a rotatable mixing drum, one end of which is a frustum with open extremity; a stationary feed hopper having a throat with a bottom opening and a side opening, the latter registering with the open extremity of the frustum of the mixing drum; a journal connection between said registering parts; a rotatable screw conveyer within the throat adapted for selectively directing material through either opening, said conveyer being connected with and deriving its rotation from the mixing drum; and a gate for controlling the bottom opening of the throat.

In testimony whereof I have signed my name to this specification.

PETER F. SCHNEIDER.
